UNITED STATES PATENT OFFICE.

LOYD C. DIBERT, OF SAN FRANCISCO, CALIFORNIA.

ROTARY AMALGAMATOR AND CONCENTRATOR.

Specification of Letters Patent. Patented July 20, 1915.

1,147,314.

Application filed October 19, 1914. Serial No. 867,492.

To all whom it may concern:

Be it known that I, LOYD C. DIBERT, a citizen of the United States, residing in the city and county of San Francisco and State of California, have invented certain new and useful Improvements in Rotary Amalgamators and Concentrators, of which the following is a specification.

My invention relates to that class of amalgamators and concentrators in which the separation is effected in a rotating cylinder or barrel.

The object of my invention is to provide a simple and efficient machine of this class, so mounted and operated as to be capable of various necessary adjustments to adapt it for accurate regulation in conformity with the requirements and character of the material to be operated upon.

To this end my invention consists in the novel rotary amalgamator and concentrator which I shall hereinafter fully describe by reference to the accompanying drawings.

Figure 1 is a side elevation of my machine. Fig. 2 is a tail-end elevation, partly broken, of the same. Fig. 3 is a top plan view, one of the cylinders or barrels being removed. Fig. 4 is a head-end elevation of my machine. Fig. 5 is a plan view, enlarged, of the feed chute with its branches and controlling switch-valve. Fig. 6 is a diagrammatic view showing one cylinder or barrel and the delivery trough with its valve for dividing the tailings. Fig. 7 is a diagrammatic view showing the body of concentrates in the cylinder or barrel. Fig. 8 is a longitudinal broken view, enlarged, partly in section and partly in elevation, showing the composite construction of the cylinder or barrel, the inner shell being shown as partly withdrawn from the outer shell.

1 is the stand of the machine.

2 is a frame adjustable within the stand. 45 3 is the amalgamating and concentrating cylinder or barrel carried by the frame 2. The barrel is adapted for longitudinal inclination so that its delivery end may be fixed above or below the horizontal. For 50 this purpose the frame 2 which carries the barrel is pivotally mounted at one end on the driving shaft 4, by the brackets or boxes 5, as shown in Fig. 4; and, at the other end, it is adapted to be raised and lowered by 55 suitable means, as, for example, by the cams

6, on the rock shaft 7, which is operated by a handle 8, and is controlled by a ratchet 7' and retaining pawl 8'.

The barrel 3 is adapted for rotation, being mounted by means of its encircling 60 flange runners 9, on the rolls 10, the tail rolls being free on their shafts 10' for better adjustment, as is shown in one instance in Fig. 3, and the head rolls being fast on the shafts 3, and driven by the bevel gears at 11, from 65 the shaft 4, as seen in Figs. 3 and 4. The shaft 4 has a driving pulley 4'.

12 is a feed hopper supported from the head end of the frame 2 and adapted to deliver into the head end of the barrel. Being 70 carried by the frame, the feed hopper maintains its position with relation to the barrel under all conditions of the barrel adjustment. The barrel at its head-end is provided with an inwardly directed flange 13 75 leaving a feed opening 14 of less diameter than the barrel but at the delivery end the barrel is open to its full diameter. The interior surface of the barrel 3 is an amalgamating surface. To so make it, the barrel 80 may be directly plated, but I prefer to make it a composite one, as is shown in Fig. 8, the outer shell being of iron and the inner shell 3' of copper and plated, as usual. To hold the two shells together the end of the 85 outer one is slotted, as shown at 15, and this slotted zone is embraced by a clamp 16. Thus the inner or plated shell may be readily inserted, and may be removed when necessary for any purpose, to be again replaced 90 or another substituted.

Under the delivery end of the barrel 3 and suspended by brackets 17' from the frame 2 is a discharge trough 17. Under this are two branches 18 and 19. In the trough 17 95 is a switch valve 20 so related to the delivery end of the barrel that its point can be turned to divide the discharged tailings as to character, and to vary this division, as I shall hereinafter more fully explain.

Longitudinally disposed within the barrel 3 is a water spray pipe 21, adapted to deliver jets of water against the inner wall of the barrel on its uprising side, as is indicated in Fig. 6. This spray pipe is turnable on its axis, within its end elbow connection 22, shown in Fig. 1, and a small wheel 22' is fitted on said pipe to enable it to be easily turned. The spray pipe is also vertically adjustable with its stand pipe 23, 110

which is mounted on stand 1 by a clamp bracket 23', as seen in Figs. 1 and 2. By turning the spray pipe on its axis, the angle or direction of the jets may be varied, and by vertical adjusting said pipe, its general position relatively to the barrel wall may be varied.

24 is the water connection for the spray pipe and 25 is its controlling cock.

10 26 is a water connection leading into the feed hopper 12, and 27 is a cock controlling this connection.

I have found it best in practice, to make my machine with twin barrels. Accordingly, I show a pair of barrels 3, side by side. Each is mounted in its own frame 2 so that each may be independently adjusted as to inclination, and each barrel is driven independently, as shown in Figs. 3 and 4, one from one side of the stand 1 and one from the other side. Each has its own feed hopper but to each hopper runs a branch 28 of a feed chute 29. In this chute 29 is a switch valve 30 by which the material delivered to the chute 29 may be directed to either branch 28 to the exclusion of the other, or distributed to both branches. Thus either barrel may be cut out when desired.

30 The operation of the machine is as follows: The material is fed to the chute 29. If it be already wet, as, for example, pulp from a battery-mortar, water may or may not be added, according to its condition; but when dry material is being operated upon, as, for example, beach sand or other auriferous sand or gravel, water is added through the pipes 26. By means of the valve 30 the material is directed through the branches 28 to the feed hoppers 12 of the two barrels 3, and by said hoppers is fed into the flanged head-ends of the barrels through the openings 14. The barrels having previously been adjusted by the cams 6 to such upward inclination as may have been found suitable, are rotated. By this rotation the material has presented to it, a very extensive amalgamating surface many times the length of the barrel, and this surface is kept clean and fresh by the water sprays from the pipes 21. Such of the precious particles as will amalgamate are thereby caught and saved. During the operation, the lighter and worthless particles flow with the water to the delivery or tail-end of the barrels, but the heavier and precious particles, not being able to advance up hill, separate from the mass and accumulate in a body against the head flange 13 and up to a level the limit of which is defined by the angle of inclination of the barrel. In this continuous separation such of the precious particles as will amalgamate are caught by the copper plate of the barrel and such as will not amalgamate remain in the barrel as concentrates.

The water sprays from the pipes 21 have the double function of keeping the amalgamating surface clean, and of washing down and helping to keep alive and agitated the uprising and advancing material, thereby promoting separation. The tailings pass off from the barrel into the delivery trough 17, but as these tailings may themselves be graded to advantage so that the heavier may be operated upon again, I have found it advantageous to use the switch valve 20 and the two branches 18 and 19. As will be seen by reference to Fig. 6, the heavier particles of the tailings tend to lag behind in the uprising movement. Now by setting the point 80 of the valve 20 as shown, the heavier tailings may be directed and delivered separately from the lighter. When the operation is complete, that is to say, when sufficient amalgamation and concentration is had, the feed of material is stopped, and the barrel is dropped to a downward inclination. The concentrates then pass out from the lower end and the barrel may be scraped of its amalgam either *in situ* or after removal of 90 the copper shell 3'.

The advantage of the independently operable and adjustable twin barrels is that one may be cut out, for the removal of its contents, or for repairs, while the other is still running, thus saving time and making the operation continuous. This is done by the switch valve 30. The vertical and axial adjustments of the spray pipe are of advantage in nicely regulating the position 100 and direction of the water jets. The adjustment of the barrels to various angles enables the operator to nicely determine their position according to the work to be done and to the material being operated upon.

I claim:—

1. In a machine of the class described, the combination of an amalgamating and concentrating barrel; means for varying the inclination of said barrel; means for rotating the barrel on its axis; and a water-spray pipe disposed within the barrel to direct its jets against the inner wall thereof on its uprising side, said spray-pipe being loosely turnable on its axis to vary the angle of its 115 jets.

2. In a machine of the class described, the combination of an amalgamating and concentrating barrel; means for varying the inclination of said barrel; means for rotating the barrel on its axis; and a water-spray pipe disposed within the barrel to direct its jets against the inner wall thereof on its uprising side, said spray pipe being vertically adjustable and also free to rotate on its longitudinal axis, and means on the pipe for imparting rotatable movement thereto.

3. In a machine of the class described, the combination of an amalgamating and concentrating barrel; means for varying the in- 130

- clination of said barrel; means for rotating the barrel on its axis; and a water-spray pipe disposed within the barrel to direct its jets against the inner wall thereof on its uprising side, said spray pipe being turnable on its axis to vary the angle of its jets and means whereby the pipe is also vertically adjustable to vary its position within the barrel.
4. In a machine of the class described, the combination of an amalgamating and concentrating barrel; means for rotating the barrel on its axis; a feed hopper at the head of the barrel; a water connection; a connection therefrom to the feed hopper; and a spray pipe from the water connection disposed within the barrel to direct its jets against the inner wall thereof on its uprising side, said spray pipe being freely turnable and means for turning the same.
5. In a machine of the class described, the combination of a rotating amalgamating and concentrating barrel; a delivery trough under the tail-end of the barrel; and a switch valve in said trough horizontally adjustable across the path of the issuing material.
6. In a machine of the class described, the combination of a pair of amalgamating and concentrating barrels; means for separately varying the inclination of said barrels; means for separately rotating them on their axis; a feed hopper at the head-end of each barrel and adjustable therewith; a feed chute, with a branch to each hopper; and a switch valve in said feed chute to direct the material into either branch alone or into both as desired.
7. In a machine of the character described, the combination of a rotating amalgamating and concentrating barrel, a delivery trough to receive the matter at the tail end of the barrel, and a switch valve pivoted at one end and horizontally adjustable across the path of the issuing material, substantially as and for the purpose described.
8. In a machine of the character described, the combination of an elongated horizontally disposed barrel, pivotally supported at its feed end, and formed at said end with an inwardly directed flange bounding a feed opening, means adjacent the opposite end of the barrel for vertically adjusting it about its pivotal connection, a hopper connected with the feed end of the barrel and leading into its feed opening, a removable copper plated lining within the barrel, the inner end of said lining covering the flange of the barrel and having an opening fitting in and coinciding with the feed opening of said barrel, means for fixedly connecting the lining to the barrel whereby the same is rotatable with the barrel, and means for rotating the barrel.
- In testimony whereof I have signed my name to this specification in the presence of two subscribing witnesses.
